GOVERNOR APPARATUS

William F. Engel, George W. La Salle, and Otis D. Treiber, Canton, Ohio, assignors to Hercules Motors Corporation, Canton, Ohio, a corporation of Ohio

Application July 3, 1934, Serial No. 733,630

15 Claims. (Cl. 264—3)

The invention relates in general to governor apparatus adapted for association with means controlling the speed of rotation of a shaft, whereby regardless of the setting of the control means the maximum speed of rotation of the shaft is maintained at a predetermined limit, and whereby a particular or idling speed of rotation of the shaft may be maintained automatically.

More particularly the invention relates to governor apparatus of the foregoing general character which is adapted for use in connection with a compression ignition internal combustion engine utilizing preferably liquid hydrocarbon fuel such as Diesel oil, and used as the motive power for a vehicle such as a truck, bus, commercial car, passenger car, or the like.

From another standpoint, the invention relates to governor apparatus of the foregoing general character and which in one form is adapted for use in connection with a compression ignition internal combustion engine utilizing preferably liquid hydrocarbon fuel such as diesel oil and used as a variable torque controlled source of power for a power shovel, in which an increase in torque is desirable with increasing engine speeds up to a predetermined intermediate engine speed which may be 900 R. P. M., after which the torque automatically falls off at a predetermined rate with a further increase in the engine speed to a second intermediate engine speed, which may be 1300 R. P. M., and after which the torque very rapidly falls off with further overrunning or increase in speed of the engine to the maximum speed.

Governor apparatus of the foregoing type for the control of vehicle motive power, have included relative complex mechanisms, which have been relatively difficult to adjust both with respect to the maximum speed governor action and the idling speed governor action.

Governor apparatus of the foregoing type and adapted for variable torque control have not been heretofore generally available.

The objects of the present improvements include in general the provision of such governor apparatus in which the construction and arrangement of the parts of the governor apparatus is simplified so as to facilitate the manufacture and maintenance of the same.

Further objects of the present improvements include the provision of governor apparatus of the foregoing description, and which includes simplified adjusting means for setting the apparatus with respect to the governor action both

at the idling and maximum speeds, such adjusting means being externally accessible.

Further objects of the present improvements include the provision of governor apparatus of the foregoing description which includes simplified and improved means for stopping the engine.

Further objects of the present improvements include the provision of governor apparatus of the foregoing description, one form of which is adapted for providing variable automatic torque control for a compression ignition internal combustion engine used as a source of power for a power shovel and the like.

Further objects of the present improvements include the provision of governor apparatus of the foregoing description, and the construction and arrangement of which is such as to permit interchangeable use of certain of the parts in the present improved apparatus or in the improved governor apparatus set forth in the prior application for U. S. Letters Patent of George W. La Salle, Serial No. 694,434, the apparatus of said prior application being particularly adapted for use in connection with a compression ignition internal combustion engine of an industrial power unit, and which is adapted among other things to provide a governor action to maintain the speed of rotation of the controlled shaft within predetermined upper and lower limits with respect to any of a plurality of set speeds.

The foregoing and other objects are attained by the improvements, apparatus, parts, combinations and sub-combinations, which comprise the present invention, and the nature of which is set forth in the following general statement, and preferred embodiments of which, together with their mode of use are set forth in the following description, and which are particularly and distinctly pointed out and set forth in the appended claims forming part hereof.

The nature of the present invention may be described in general terms as including a rotary shaft, power drive means for the shaft, variable control means controlling the operation of the power drive means and adapted to be set to vary the speed of rotation of the shaft, control setting means operatively associated with the control means for varying the setting of the same, and governor means operatively associated with the control setting means and with the control means and operative by governor action to maintain the speed of rotation of the shaft within predetermined limits with respect to an idling speed, and operative by governor action to limit the maxi-

mum speed of rotation of the shaft, the governor means including centrifugally actuated governor weights, externally accessible simplified means for adjusting the maximum speed at which the governor action takes place, and externally accessible simplified means for adjusting the idling speed governor action of the apparatus.

10 Improved variable control setting means are provided, by which very accurate initial adjustments of the control setting means may be made.

In the form of the improved governor apparatus adapted for use in connection with an engine for providing variable torque for a power shovel and the like, means are provided whereby two successive intermediate governor actions take place at predetermined speeds after each of which a different change in the torque of the engine is obtained.

The improved apparatus furthermore includes improved means for stopping the engine associated with parts of the improved adjustable means for setting the idling speed of the engine.

25 means for setting the running speed of the engine. The improved governor apparatus is preferably included in and/or combined with a compression ignition internal combustion engine as is hereinafter set forth in greater detail, and the engine and apparatus also may include further novel improvements illustrated in the drawings and/or as hereinafter set forth.

30 Embodiments of the improved governor apparatus are illustrated in the accompanying drawings forming part hereof, in which

Figure 1 is a side elevation view of a compression ignition internal combustion engine having a fuel pump equipped with one embodiment of the improved governor apparatus of the present invention and being adapted for use as the motive power of a vehicle;

40 Fig. 2, an enlarged transverse sectional view of the improved governor apparatus, as on line 2-2, Fig. 1, distant parts of the engine and fuel pump being removed;

45 Fig. 3, a fragmentary side elevation with portions broken away of the improved governor apparatus and portions of the fuel pump, distant parts of the engine being removed;

Fig. 4, an enlarged fragmentary longitudinal sectional view of the improved governor apparatus and portions of the fuel pump, distant parts of the engine being removed, as on line 4-4, Fig. 2.

Fig. 2.
Fig. 5, a fragmentary elevation with portions broken away of the improved governor apparatus, illustrating the side thereof opposite to the side shown in Fig. 3, and showing the details of the improved stop means and parts of the variable adjusting means for the governor apparatus; and

60 Fig. 6, a view similar to Fig. 4 illustrating another embodiment of the improved governor apparatus adapted for automatically providing a variable torque control for an engine used as a power source for a power shovel or the like.

Similar numerals refer to similar parts throughout the several views.

35 A compression ignition internal combustion engine equipped with one embodiment of the present improved governor apparatus is indicated generally at 10 in Figs. 1 to 5, inclusive, and as 70 illustrated is a six cylinder, four stroke cycle, single action, high speed, compression ignition internal combustion engine, in which the air for combustion is obtained normally directly from the atmosphere, and in which separate quantities 75 or charges of the preferred liquid hydrocarbon

fuel, such as Diesel oil, are successively injected by operation of a fuel pump indicated generally by 11, into the combustion chambers of the engine at successive timed intervals, one charge being injected into the combustion chambers of each cylinder during each four stroke cycle of the piston operatively mounted in the cylinder.

The fuel pump 11 is operatively mounted on one side of the engine as shown in Fig. 1, and as illustrated is of usual construction and arrangement and is a Bosch fuel injection pump, made by Robert Bosch, A. G., Stuttgart, Germany, and includes a shaft 12, driven by an operative connection with gearing contained in a gear housing 13 of the engine, the gears in the gear housing being driven by the engine crank shaft. The gears and crank shaft are not shown, and may be of a usual construction and arrangement.

The fuel pump 11 includes a casing 14 in which plunger pistons, not shown, are operatively mounted, each in a pump cylinder, not shown, formed in the casing 14, one pump plunger piston and cylinder being provided for each cylinder of the engine. 20

The plunger pistons are actuated in a usual manner by cams on a cam shaft portion, not shown, of the shaft 12, the cam shaft portion being located within a cam shaft chamber of the casing 14.

Each pump cylinder communicates with a discharge outlet 15 which communicatingly connects with one end of a tube 16, the other end of which communicatingly connects with a pintle nozzle discharging into the combustion chambers of one of the engine cylinders. 35

The liquid fuel is supplied to the pump 11 through a main supply tube 17 in which an oil cleaner 18 may be interposed ahead of the fuel pump 11.

The fuel pump is provided with the present improved governor apparatus indicated generally by 19, and the fuel pump also includes valve or variable metering means for each fuel pump cylinder controlling the quantity of liquid fuel admitted to each pump cylinder from the main supply tube 17, and thus controlling the quantity of fuel in each charge pumped out of each pump cylinder into its associated engine cylinder combustion chambers on the pressure stroke of the piston of the pump cylinder.

The fuel pump 11 furthermore includes a valve setting or throttle rod 20 which is operatively associated with each of the valve means for each of the pump cylinders and which is arranged for reciprocation in normally horizontal opposite directions in the casing 14 of the fuel pump. 11

The rod 20, when displaced to its extreme position in the direction of the arrow S, in Figs. 3 and 4 actuates the valve means so as to shut off the flow of liquid fuel into the pump cylinders, and thus stops the engine. At the position of the rod 20 and associated parts as illustrated in full lines in Figs. 3 and 4, the pump valve means are set to a position for permitting a flow of fuel into the pump cylinders at such rate as to cause the engine 10 to operate at a desired idling speed. 60 65

Displacement of the rod 20 in the direction of the arrow F actuates the pump valve means to increase the rate of flow of liquid fuel into the 70 pump cylinders, the greater the displacement of the rod 20 in the direction of the arrow F, the greater the rate of flow of liquid fuel into the pump cylinders.

Accordingly the valve means of the pump cyl. 75

inders may be termed control means determining the speed of operation of the engine, and the rod 28 may be termed a control means actuating member which is movable between two extreme 5 positions, one of which is such that the control means are actuated to stop the engine or apparatus controlled by the control or valve means, and the other of which is such that the control means are actuated so as to run the engine at 10 full speed, and intermediate positions of which include a setting which provides an idling speed for the engine, and provides for varying speeds thereof between the idling speed and the full speed.

15 The governor apparatus 19 preferably includes a casing indicated generally by 21 and which comprises walls forming a governor chamber 22, and which in the illustrated embodiment consists of two casing sections 23 and 23' secured to each 20 other, and the casing section 23' being secured to the pump casing 14.

The governor casing section 23' includes an end wall 24 which abuts against the adjacent end wall 25 of the pump casing 14, and the governor drive end 26 of the pump shaft 12 extends through suitable apertures formed in the pump casing wall 25 and the governor casing wall 24, and preferably anti-friction bearing means indicated generally by 27 journal the shaft in the governor casing wall 24, and the governor drive end 26 of the pump shaft 12 terminates within the governor chamber 22.

35 A governor drive gear 28 is secured upon the governor drive end 26 of the pump shaft 12 within the governor chamber 22, and also within the governor chamber, a governor shaft 29 is journal mounted at opposite ends as by means of anti-friction bearing means indicated generally by 30 and 31, respectively, which are themselves respectively mounted in the governor casing end wall 24, and on the opposite governor casing end wall 32.

45 The longitudinal axis of rotation of the governor shaft 29 is preferably parallel with the longitudinal axis of rotation of the pump shaft 12 and the governor shaft has secured thereon a driven pinion 33 which is located adjacent the anti-friction bearing means 30 and which is meshed with the governor drive gear 28, whereby 50 rotation of the pump shaft 12 driven as aforesaid from the crank shaft of the engine, serves to rotate the governor shaft 29.

The governor shaft 29 has secured thereon, in the illustrated embodiment adjacent the driven pinion 33, a spider 34 having sets of arms 35 and 35' respectively extending from diametrically opposite sides of the shaft 29, and governor weights 36 and 36' are pivotally mounted intermediate their ends respectively on the opposite sets of spider arms 35 and 35', as by means of spider pins 37 and 37', the longitudinal axes of which are parallel, and which are spaced at equal distances from the longitudinal axis of the governor shaft 29, and lie in a plane normal to the longitudinal axis of the shaft 29.

65 The governor weights 36 and 36' are of a desired shape, and are substantially identical with each other, and have their centers of gravity located at equal distances from the longitudinal axes of the pins 37 and 37' beyond the outer extremities of the sets of spider arms 35 and 35'.

The governor weights 36 and 36' include respectively sleeve actuating tongues 38 and 38' which extend toward the governor shaft 29, the 70 tongues 38 and 38' being located between the

spider pins 37 and 37' and the governor shaft 29. The governor weights 36 and 36' also include at their inner extremities stop tongues 39 and 39' which abut against opposite stop faces on the spider hub 40 and limit the outward movement of the weights 36 and 36' under the action of the centrifugal forces set up therein by rotation of the shaft 29.

A sleeve 41 is slidably mounted on the governor shaft 29 between the spider 34 and the outer bearing means 31 for the governor shaft 29, and the end face 42 of the sleeve 41 adjacent the tongues 38 and 38' of the governor weights 36 and 36' is abuttable by the outer extremities of the tongues 38 and 38', and the sleeve 41 is longitudinally movable on the shaft 29.

Intermediate its ends, the sleeve 41 has rotatably mounted thereon a ring 43, the mounting of the ring 43 on the sleeve 41 being preferably as illustrated by means of an anti-friction bearing 44.

The governor apparatus 19 furthermore includes a yoke lever pivoting eccentric shaft 45 which is journaled at its ends in the opposite side walls 46 and 47 of the governor casing section 23, and which is located at one side of, and as illustrated, normally below the governor shaft 29, the longitudinal axis of the eccentric shaft 45 extending at right angles to the direction of the longitudinal axis of the governor shaft 29.

A yoke lever 48 is pivotally mounted at one end 49 on the eccentric shaft 45, and the yoke lever end 49 as illustrated is the lower end of the yoke lever 48.

The yoke lever 48 has formed therein a central opening 50, and the governor shaft 29, the sleeve 41, and the ring 43 rotatably mounted on the sleeve 41 as aforesaid, extend through and/or are located within the central opening 50 of the yoke lever 48.

The yoke lever 48 includes side members 51 and 51' comprising in part the boundary members for the opening 50 and the yoke side members 51 and 51' are located on opposite sides of the shaft 29, the sleeve 41 and the ring 43.

The ring 43 has formed in its outer peripheral surface an outwardly opening annular groove 52 and pins 53 and 53' have their outer ends respectively secured in the yoke side members 51 and 51' and have their inner ends extending into the ring groove 52.

At the upper corner of the yoke lever 48 opposite the outer end of the rod 28, a connector ear 54 is provided and a longitudinally adjustable link means 55 is pivotally connected at its outer end with the ear 54, as by pin means 56, and the link means 55 is pivotally connected at its inner end with the outer extremity of the rod 28 as by pin means 57.

60 Preferably a compression spring 70 is interposed between the upper end of the yoke lever 48, and an externally threaded adjustable screw plug 71 screwed in an internally threaded bore formed in the governor casing wall 32, the upper end of the yoke lever 48 and the plug 71 preferably having oppositely opening sockets formed therein into which the opposite ends of the compression spring 70 extend.

The compression spring 70 and the screw plug 71 may be termed externally accessible means 70 adjustably determining the idling speed governor action of the apparatus, after the manually operative control means have been set, as herein-after set forth.

75 For the purposes of the present improvements, 75

the anti-friction bearing means 31 for the governor shaft 29 is carried in externally accessible means indicated generally by 72 for adjusting and determining the maximum speed at which 5 governor action takes place, as aforesaid.

The maximum speed governor action adjusting means 72 includes a tubular member 73, which is preferably externally cylindric in its 10 central portions and whose externally cylindric central portions fit in a cylindric bore formed in the governor casing end wall 32, the ends of the tubular member 73 extending beyond opposite sides of the casing end wall 32, and the inner end 15 of the tubular member 73 being provided within the governor chamber 22 with an inwardly extending annular flange 74.

The tubular member 73 on the outside of the casing wall 32 is provided with an outwardly extending annular flange 75, and initial clearance 20 shims 76 are interposed between the flange 75 and the wall 32.

The outer end 77 of the tubular member 73 extends outwardly beyond the flange 75.

A bearing and adjusting means mounting cap 25 78 is mounted on the outer end 77 of the tubular member 73.

The cap 78 is provided with an internal socket 80 formed to seat at its outer end the outer raceway member 31a of the ball anti-friction bearing 30 means 31 illustrated, the inner raceway member 31b of which mounts the outer end of the governor shaft 29, as aforesaid.

The cap socket 80 has rotatably mounted 35 therein in rotary abutment with the inner side of the outer raceway member 31a of the ball anti-friction bearing means 31, a ring 81 which is provided with external worm wheel threads 82 and the bore 83 of which is substantially larger in diameter than the diameter of the shaft 29 which extends therethrough.

The socket 80 includes an enlarged inner end 40 portion or counterbore 84 which fits on the outer end 77 of the tubular member 73, and the outer extremity of the tubular member 73 terminates intermediate the ends of the enlarged portion 84 45 of the cap 78, and a spring seat member 86 is located in the counterbore 84 between the ring 81 and the outer extremity of the tubular member 73.

The spring seat member 86 includes a central 50 sleeve hub 87 through the bore of which the shaft 29 passes and which extends into the bore 83 of the ring 81, the hub 87 and the ring 81 being screw connected with one another by internal threads 88-1 in the bore 83 of the ring, and external threads 88-2 on the hub 87.

For preventing rotary movement of the spring seat member 86, a tongue and notch connection 60 thereof with the outer end 77 of the tubular member 73 is provided, as illustrated by tongues 86-1 extending from the seat member 86 into the openings of notches 77-1 formed in the outer end 77 of the tubular member 73.

The cap 78 has journal mounted therein a worm 65 screw 89 having a screw head 90 located externally of the cap 78, and the worm screw 89 is meshed with the worm threads 82 formed externally in the ring 81, and accordingly rotation of the worm screw 89 serves to turn the ring 81, and the spring seat 86 screw connected with the ring 81 and 70 prevented from rotation by its end tongue and notch connection with the tubular member 73, is caused to be displaced with respect to the tubular member 73.

75 A reacting ring 91 extends through the opening

of the annular flange 74 of the tubular member 73, and the reacting ring 91 is provided within the bore of the tubular member 73 with an outwardly extending annular flange 92 normally abutting against the inwardly extending annular flange 74 of the tubular member 73. 5

The reacting ring 91 is provided on its end within the governor chamber 22 with an inwardly extending annular flange 93 and a compression spring 94 is interposed between the spring seat 10 member 86 and the inwardly extending annular flange 93 of the reacting ring 91.

The cap 78 as illustrated is provided at its inner end with a flange 95 and a gasket 96 is 15 preferably interposed between the flange 95 and the flange 75 of the tubular member 73, and screws 97 preferably secure and seal the flange 95 to the flange 75 whereby the maximum speed governor action adjusting means 72 above described including the tubular member 73, the cap 20 78 and the parts operatively mounted therein, may be preassembled as a unit and may be easily inserted upon or removed from the outer end of the shaft 29.

Cap screws 98 are provided as shown for securing the unitary maximum speed governor action 25 adjusting means 72 to the wall 32.

The eccentric shaft 45 includes an eccentric portion 45a on which the yoke lever end 49 is pivotally or rotatably mounted as aforesaid, and 30 the eccentric shaft 45 furthermore includes axially aligned end journal portions 45b and 45c which are rotatably mounted respectively in the governor casing side walls 46 and 47, and the journal portion 45b of the eccentric shaft 45 extends 35 beyond the outer side of the casing side wall 47 and has secured thereon externally of the governor casing 21, a control setting lever 68-2, the outer end of which is operatively connected in a usual manner with the accelerator pedal or lever, 40 not shown, of the automotive vehicle which may be powered by the engine 10.

The eccentric shaft 45 is thus arranged to rotate about the axis 99 of the journal portions 45b and 45c as indicated by the dot-dash line 45 in Fig. 2, and at the intersection of dot-dash lines in Fig. 4, and the center axis of the eccentric portion 45a of the eccentric shaft 45 is indicated at 100 in Fig. 4, by intersecting dot-dash lines, one of which 101 passes through the center axis 50 99 of the journal portions 45b and 45c, and the dot-dash line 101 is thus the eccentric lever or crank arm of the eccentric shaft 45, which swings about the center axis 99.

As is more fully set forth in the following 55 description of the operation of the improved governor apparatus 19, swinging of the eccentric lever arm 101 in the direction of the arrow F', Fig. 4, serves to increase the speed of the engine 10, and swinging of the eccentric lever arm 101 in the 60 direction of the arrow S', Fig. 4, serves to decrease the speed of the engine 10.

The parts of the governor apparatus 19 as 65 illustrated in the drawings are in their several relative positions by which idling speed of the engine is obtained.

As best shown in Fig. 4, the maximum speed governor action adjusting means 72 is provided with an initial clearance by means of the shims 76, whereby the outer face of the flange 93 is 70 normally spaced a slight distance from the anti-friction bearing 44, and the tendency of the governor weights 36 and 36' to move the sleeve 41 and the yoke lever 48 towards the casing wall 32 is opposed by the spring 70, which is so adjusted 75

that a slight increase in the speed of the engine beyond the idling speed will cause the weights 36 and 36' to move outwardly and will slightly advance the yoke lever 48 pivoting about the center axis 39 of the eccentric portion 45a of the eccentric shaft 45 towards the flange 33, and will thus move the rod 28 in the direction of the arrow S and will slightly decrease the rate of flow of fuel and slow down the engine speed to 10 the idling speed; and on the other hand a slight decrease in the speed of the engine will permit the spring 78 to move the yoke arm 48 towards the fuel pump and cause the weights 36 and 36' to move inwardly and the rod 28 will move in the direction of the arrow F and will slightly increase the rate of flow of fuel and the speed of the engine to the idling speed, all of which may be termed a governor action at the particular idling speed setting.

20 In the normal operation of the engine, the loading of the spring 94 is such as to resist any displacement of the sleeve 41 and the ring 43 carried thereby on the bearing 44 by virtue of the forces applied to the sleeve 41 by the tongues 38 and 38' of the weights 36 and 36' due to the varying centrifugal forces acting upon the weights 36 and 36' and tending to throw the same outwardly about the pins 37 and 37'.

Accordingly during normal operation of the engine, swinging the control setting lever 68-2 in the usual manner by stepping upon the accelerator pedal or swinging the accelerator lever causes the eccentric shaft lever arm 101 to swing about the center axis 39, thus pivoting the yoke lever 48 about the pins 33 and 33' so that when the eccentric shaft lever arm 101 is swung in the direction of the arrow F', the rod 28 will be moved in the direction of the arrow F so as to increase the rate of flow of fuel and the speed of the engine, and conversely swinging of the eccentric shaft lever arm 101 in the direction of the arrow S' will move the rod 28 in the direction of the arrow S and decrease the rate of flow of fuel and the speed of the engine.

45 Excepting at the idling speed as aforesaid, as long as the speed of the engine, and consequently the speed of the governor shaft 29 does not exceed a predetermined maximum, established by the loading of the spring 94, no governor action whatever takes place.

If, however, by accident, or during a release of the engine clutch, or otherwise, regardless of the setting of the control setting lever 68-2 and the eccentric shaft 45, the speed of the engine and 55 consequently the speed of the governor shaft 29 exceeds the set maximum speed, then the force tending to move the sleeve 41, and the anti-friction bearing 44 and the ring 43 exceeds the opposing force of the spring 94, compression of the 60 spring 94 takes place, and the yoke lever 48 pivots about the eccentric portion 45a of the shaft 45 towards the casing wall 32, thus moving the rod 28 in the direction of the arrow S and reducing the rate of flow of fuel and the speed of the engine to the desired maximum speed, reducing the force on the sleeve 41 opposing the force of the 65 spring 94, and permitting the extension of the spring 94 to its position to maintain the maximum governed speed.

70 Loading of the spring 94 to establish the maximum speed of the engine is effected by turning the external screw head 90 of the worm screw 89.

75 Preferably the eccentric shaft 45 is mounted in the casing side walls 46 and 47, by providing in each of the opposite side walls 46 and 47 aligned

bores 102 and 103, respectively, the diameters of the bores 102 and 103 being large enough to permit the endwise insertion and removal therethrough of the eccentric shaft 45.

The bore 102 of the wall 46 has removably secured therein a bearing and bracket plug 104 which has a bearing bore journaling the eccentric shaft journal portion 45c; and the bore 103 in the wall 47 has removably secured therein a bearing plug 105 which has a bearing bore therein journaling the eccentric shaft journal portion 45b.

The control setting lever 68-2 is preferably adjustably secured on the external end of the shaft portion 45b as best shown in Figs. 3 and 4 by 15 worm screw and worm wheel means indicated generally by 106 and which include a worm wheel 107 secured on the shaft portion 45b and the worm wheel 107 is engirdled by a split ring hub 108 provided on the lever 68-2 and a worm screw 20 109 is journalled and extends through opposite split portions 110 and 111 of the hub and the threads of the screw 109 are meshed with the threads of the worm wheel 107, whereby rotation of the worm screw enables adjustment of the position of the arm 68-2, to the proper position with respect to the mechanism of the apparatus within the casing 21 and with respect to the external connections to the accelerator pedal or 25 like control for the engine.

30 The outer screw end of the worm screw 109 preferably is provided with a lock or clamping nut 112.

A maximum speed stop pin 113 is secured on a 35 plate 114 interposed between the hub 108 and the plug 105 and secured to the plug 105 and the hub 108 has a maximum speed stop tongue 115 extending therefrom and adapted to stop abut against the pin 113.

Within the bore 103 the end of the plug 105 is 40 notched to form a stop face 116 adapted to be abutted by a pin 117 extending from the opposite end of the eccentric portion 45a to limit motion of the eccentric in the direction causing a shutting off of the fuel supply.

The plug and bracket 104 as best shown in Fig. 5 is secured to the outer side of the casing wall 46 and the eccentric shaft portion 45c extends beyond the outer face of the plug and bracket 104 and has associated therewith preferably adjustable idling 50 speed setting and engine stop means indicated generally by 118 which prevents rotation of the shaft 45 in the fuel shutting off direction normally beyond a position permitting governor controlled idling speed operation of the engine.

The idling speed setting and engine stop means 55 118 preferably include a single tooth ratchet split ring 119 engirdling a worm wheel 120 which is secured on the shaft end portion 45c, and a worm screw 121 extends through aligned bores in opposite split ends 122 and 123 of the ring 119, and the threads of the screw 121 are meshed with the threads of the worm wheel 120 whereby minute adjustment of the position of the tooth 124 of the ratchet ring 119 with respect to the shaft 45 and 60 the other parts of the apparatus within the casing 21 is attained.

A hook pawl 125 is pivotally mounted on the bracket 104 and the hook pawl 125 includes a stop hook end 126 which is urged towards the shaft 45c 70 by spring means 127 and provides a releasable idling speed stop adapted to impinge the ratchet tooth 124 and prevent further rotation of the eccentric shaft 45 beyond the idling speed setting thereof.

For permitting stopping of the engine, the pawl 125 includes a release arm 128 which as illustrated is connected as by a wire 129 with the dash board or the like of the vehicle or other apparatus with 5 which the governor means 19 is associated, and by pulling the wire 129, the pawl stop hook end 126 is released for engagement from the tooth 124 permitting further rotation of the shaft 45 in the fuel shutting off direction so as to stop the engine.

10 In Fig. 6 a modified embodiment 19' of the improved governor apparatus is illustrated, and the governor apparatus 19' is adapted for a variable torque control of a Diesel engine, such as the engine 10 when used as a power supply for a 15 power shovel.

The parts of the governor apparatus 19' as illustrated are identical with the parts of the apparatus 19 heretofore described, with the following exceptions.

20 In the governor apparatus 19', the spring 94 is not utilized and there is interposed between the reaction member 91 and the spring seat member 86 an intermediate double spring seat and stop member 130 including a sleeve portion 131 from 25 which extends an annular flange 132 opposite the reacting member flange 93.

The member 130 also includes an outwardly extending annular stop and spring seat flange 133 which is opposite the spring seat member 86 and 30 which normally abuts against a shoulder 134 formed in the end of the tubular member 73 adjacent the shoulder flange 74.

A compression spring 135 is interposed between 35 and reacts against the adjustable spring seat member 86 and the flange 133 of the intermediate member 130, and another compression spring 136 is interposed between the reacting member flange 93 and the flange 132 of the intermediate member 130.

40 The resistance or loading of the springs 135 and 136 are different from each other, the spring 136 having the least initial load, and the rate of deflection however of the spring 135 is greater than the rate of deflection of the spring 136.

45 Accordingly when the speed of the engine, as in a power shovel, reaches for example 900 R. P. M., the force tending to move the sleeve 41 and the yoke lever 48 becomes such as to pivot the yoke lever 48 about the eccentric portion 45a of the shaft 45 toward the casing wall 32 compressing the spring 136 and cutting off the fuel supply of the engine so as to reduce the torque of 50 the same while the engine speed is further increased.

55 After the engine speed has increased to 1300 R. P. M. for example, the reacting member 91 abuts against the intermediate member 130 and the force tending to move the sleeve 41 may then have attained such magnitude as to rapidly compress the spring 135 and rapidly shut off the 60 supply of fuel to the engine until if desired the entire fuel supply is shut off.

In the practical operation of a power shovel for 65 example, the normal shovel speed may be 1300 R. P. M., and accordingly when the shovel engine is controlled by the improved governor apparatus 19', when the shovel strikes a rock or other obstruction, reducing the speed of the engine, extra torque is available as the speed of the engine reduces to 900 R. P. M. at which speed the torque is a maximum.

We claim:

1. Governor controlled apparatus including a 75 rotary shaft, power drive means for the shaft, variable control means controlling the operation of the power drive means and the speed of rota-

tion of the rotary shaft driven thereby, control setting means operatively associated with the control means for varying the setting of the same, and governor means operatively associated with the power drive means and with the control means and with the control setting means, the governor means including a lever operating the variable control means and operated by the control setting means, centrifugally operating means pivotally and slidably associated with the lever intermediate its ends and connected for rotation by the shaft and adapted to apply a force in one direction against the lever, and resilient means applying a force in the opposite direction against the lever, the lever adjacent one end thereof having an operative connection with the variable control means, and the control setting means including a crank pivotally mounting the lever adjacent the other end thereof, and the resilient means being loaded so as to prevent movement of the lever by the action of the centrifugally induced force of the governor means during a normal speed range of the rotary shaft. 10 15

2. Governor controlled apparatus including a 20 rotary shaft, power drive means for the shaft, variable control means controlling the operation of the power drive means and the speed of rotation of the rotary shaft driven thereby, control setting means operatively associated with the control means for varying the setting of the same, and governor means operatively associated with the power drive means and with the control means and with the control setting means, the 25

variable control means and operated by the control setting means, centrifugally operating means pivotally and slidably associated with the lever intermediate its ends and connected for rotation by the shaft and adapted to apply a force in one 30 direction against the lever, and adjustable resilient means applying a force in the opposite direction against the lever, the lever adjacent one end thereof having an operative connection with the variable control means, and the control setting means including a crank pivotally mounting the lever adjacent the other end thereof, and the 35

resilient means being loaded so as to prevent movement of the lever by the action of the centrifugally induced force of the governor means during a normal speed range of the rotary shaft. 40

3. Governor controlled apparatus including a 45 rotary shaft, power drive means for the shaft, variable control means controlling the operation of the power drive means and the speed of rotation of the rotary shaft driven thereby, control setting means operatively associated with the control means for varying the setting of the same, and governor means operatively associated with the power drive means and with the control means and with the control setting means, the 50

variable control means and operated by the control setting means, centrifugally operating means pivotally and slidably associated with the lever intermediate its ends and connected for rotation by the shaft and adapted to apply a force in one 55 direction against the lever, and resilient means including a spring pressed reacting member located at the side of the lever opposite the direction of the centrifugally applied force, and the spring pressed reacting member being adapted to be abutted by the lever and resist movement thereof by the action of the centrifugally applied force, the lever adjacent one end thereof having an operative connection with the variable 60

control setting means, centrifugally operating means pivotally and slidably associated with the lever intermediate its ends and connected for rotation by the shaft and adapted to apply a force in one 65 direction against the lever, and resilient means including a spring pressed reacting member located at the side of the lever opposite the direction of the centrifugally applied force, and the spring pressed reacting member being adapted to be abutted by the lever and resist movement thereof by the action of the centrifugally applied force, the lever adjacent one end thereof having an operative connection with the variable 70

control setting means, centrifugally operating means pivotally and slidably associated with the lever intermediate its ends and connected for rotation by the shaft and adapted to apply a force in one 75 direction against the lever, and resilient means including a spring pressed reacting member located at the side of the lever opposite the direction of the centrifugally applied force, and the spring pressed reacting member being adapted to be abutted by the lever and resist movement thereof by the action of the centrifugally applied force, the lever adjacent one end thereof having an operative connection with the variable 75

control means, and the control setting means including a crank pivotally mounting the lever adjacent the other end thereof, and the resilient means being loaded so as to prevent movement of the lever by the action of the centrifugally induced force of the governor means during a normal speed range of the rotary shaft.

4. Governor controlled apparatus including a rotary shaft, power drive means for the shaft, variable control means controlling the operation of the power drive means and the speed of rotation of the rotary shaft driven thereby, control setting means operatively associated with the control means for varying the setting of the same, and governor means operatively associated with the power drive means and with the control means and with the control setting means, the governor means including a lever operating the variable control means and operated by the control setting means, centrifugally operating means pivotally and slidably associated with the lever intermediate its ends and connected for rotation by the shaft and adapted to apply a force in one direction against the lever, and resilient means including an adjustable spring pressed reacting member located at the side of the lever opposite the direction of the centrifugally applied force, and the spring pressed reacting member being adapted to be abutted by the lever and resist movement thereof by the action of the centrifugally applied force, the lever adjacent one end thereof having an operative connection with the variable control means, and the control setting means including a crank pivotally mounting the lever adjacent the other end thereof, and the resilient means being loaded so as to prevent movement of the lever by the action of the centrifugally induced force of the governor means during a normal speed range of the rotary shaft.

5. Governor controlled apparatus including a rotary shaft, power drive means for the shaft, variable control means controlling the operation of the power drive means and the speed of rotation of the rotary shaft driven thereby, control setting means operatively associated with the control means for varying the setting of the same, and governor means operatively associated with the power drive means and with the control means and with the control setting means, the governor means including a lever operating the variable control means and operated by the control setting means, centrifugally operating means pivotally and slidably associated with the lever intermediate its ends and connected for rotation by the shaft and adapted to apply a force in one direction against the lever, and resilient means including a spring pressed reacting member located at the side of the lever opposite the direction of the centrifugally applied force, and the spring pressed reacting member being adapted to be abutted by the lever and resist movement thereof by the action of the centrifugally applied force, and resilient means adapted to apply a second force upon the lever in the opposite direction to the centrifugally applied force, the lever adjacent one end thereof having an operative connection with the variable control means, and the control setting means including a crank pivotally mounting the lever adjacent the other end thereof, and the resilient means being loaded so as to prevent movement of the lever by the action of the centrifugally induced force of the governor means during a normal speed range of the rotary shaft.

6. In governor apparatus and the like, adjust-

able resilient reacting means including a longitudinally extending mounting member having a stop flange at one end, a reacting member mounted for longitudinal movement with respect to the mounting member, the reacting member having a flange normally abutting against the mounting member stop flange, a spring seat member, means adjustably mounting the spring seat member on the mounting member with the reacting member located between the mounting member stop flange and the spring seat member, a compression spring interposed between the reacting member and the spring seat member, the spring seat member mounting means including a rotary member operatively associated with the spring seat member whereby rotation of the rotary member moves the spring seat member longitudinally for varying the loading of the spring, the rotary member having worm wheel threads thereon and a worm screw operatively associated with the worm wheel threads for turning the rotary member.

7. In governor apparatus and the like, unitary adjustable resilient reacting means including a longitudinally extending tubular mounting member having a stop flange at one end, a reacting member mounted for longitudinal movement with respect to the tubular member, the reacting member having a flange within the bore of the tubular member and normally abutting against the tubular member stop flange, a cap secured on the other end of the tubular member, the cap having a longitudinally extending socket formed therein and comprising a longitudinal extension of the bore of the tubular member, a spring seat member located within the socket, a compression spring interposed between the reacting member and the spring seat member, a rotary member rotatably mounted in the socket and operatively associated with the spring seat member whereby rotation of the rotary member moves the spring seat member longitudinally for varying the loading of the spring, the rotary member having worm wheel threads thereon, a worm screw rotatably mounted in the cap and operatively associated with the worm wheel threads, and the worm screw having a head located externally of the cap whereby the worm screw head may be turned from without the cap and the rotary member is turned thereby to adjust the position of the spring seat member.

8. In governor apparatus and the like, a casing, governor controlled valve setting means operatively mounted within the casing, means for varying the setting of the valve setting means including a shaft operatively associated with the valve setting means within the casing, the shaft extending externally of the casing, a control lever, and means adjustably mounting the control lever on the shaft outside of the casing, the means adjustably mounting the control lever on the shaft including interacting members on the lever and the shaft adapted for operation to vary and set the angular position of the lever with respect to an element of the shaft.

9. In governor apparatus and the like, a casing, governor controlled valve setting means operatively mounted within the casing, a shaft operatively associated with the valve setting means within the casing, the shaft extending externally of the casing, the shaft being adapted for manual rotation outside of the casing for varying the setting of the valve setting means within the casing, means outside of the casing for releasably stopping rotation of the shaft in one

direction beyond a position establishing an intermediate governor controlled setting of the valve setting means within the casing.

10. In governor apparatus and the like, a casing, governor controlled valve setting means operatively mounted within the casing, a shaft operatively associated with the valve setting means within the casing, the shaft extending externally of the casing, the shaft being adapted for manual rotation outside of the casing for varying the setting of the valve setting means within the casing, means outside of the casing for releasably stopping rotation of the shaft in one direction beyond a position establishing an intermediate governor controlled setting of the valve setting means within the casing, and means for manually releasing the releasable stop means from stopping relationship with the shaft.

11. In governor apparatus and the like, a casing, governor controlled valve setting means operatively mounted within the casing, a shaft operatively associated with the valve setting means within the casing, the shaft extending externally of the casing, the shaft being adapted for manual rotation outside of the casing for varying the setting of the valve setting means within the casing, means outside of the casing for releasably stopping rotation of the shaft in one direction beyond a position establishing an intermediate governor controlled setting of the valve setting means within the casing, the releasable stop means including a ratchet secured on the shaft, the ratchet having a single stop tooth, and a pawl associated with the ratchet and normally maintained in position for engaging the ratchet stop tooth.

12. In governor apparatus and the like, a casing, governor controlled valve setting means operatively mounted within the casing, a shaft operatively associated with the valve setting means within the casing, the shaft extending externally of the casing, the shaft being adapted for manual rotation outside of the casing for varying the setting of the valve setting means within the casing, means outside of the casing for releasably stopping rotation of the shaft in one direction beyond a position establishing an intermediate governor controlled setting of the valve setting means within the casing, the releasable stop means including a ratchet secured on the shaft, the ratchet having a single stop tooth, and a pawl associated with the ratchet and normally maintained in position for engaging the ratchet stop tooth, and means for moving the pawl out of position for stop engagement with the ratchet tooth.

13. Governor controlled apparatus including a rotary shaft, power drive means for the shaft, variable control means controlling the operation of the power drive means and the speed of rotation of the rotary shaft driven thereby, control

setting means operatively associated with the control means for varying the setting of the same, and governor means operatively associated with the power drive means and with the control means and with the control setting means, the governor means including a movably mounted lever operating the variable control means and operated by the control setting means, centrifugally operating means associated with the lever and with the rotary shaft and adapted to apply a force in one direction against the lever, and resilient reacting means operative to opposed movement of the lever by the action of the centrifugally applied force, the resilient reacting means including a plurality of springs arranged to deflect successively under the action of the centrifugally applied force, each spring having a different rate of deflection.

14. In governor apparatus and the like, resilient reacting means including a longitudinally extending mounting member having a stop flange at one end, a reacting member mounted for longitudinal movement with respect to the mounting member, the reacting member having a flange normally abutting against the mounting member stop flange, a first spring seat member mounted on the mounting member with the reacting member located between the mounting member stop flange and the first spring seat member, an intermediate spring seat member located between the reacting member and the first spring seat member, a first compression spring interposed between the first spring seat member and the intermediate spring seat member and a second compression spring interposed between the intermediate spring seat member and the reacting member.

15. In governor apparatus and the like, resilient reacting means including a longitudinally extending mounting member having a stop flange at one end, a reacting member mounted for longitudinal movement with respect to the mounting member, the reacting member having a flange normally abutting against the mounting member stop flange, a first spring seat member mounted on the mounting member with the reacting member located between the mounting member stop flange and the first spring seat member, an intermediate spring seat member located between the reacting member and the first spring seat member, a first compression spring interposed between the first spring seat member and the intermediate spring seat member and a second compression spring interposed between the intermediate spring seat member and the reacting member, the springs having different rates of deflection.
